DOOR LOCK

Filed March 12, 1925

UNITED STATES PATENT OFFICE

JOHN HOLTZMAN, OF NEW YORK, N. Y.

DOOR LOCK

Application filed March 12, 1925. Serial No. 14,980.

This invention relates to door securing means and has as one of its objects to provide simple, effective and novel types of locks, that may be readily applied and easily operated.

Another purpose is to produce a lock, operable by a knob on one side of the door or a key on the other and having a double swinging bolt of unusual sturdiness engageable with a rigid, firmly anchored keeper.

With this and other objects in mind, reference is had to the attached sheet of drawings illustrating practical embodiments of the invention, and in which:—

15. Figure 1 is a plan view of one type of door lock made in accordance with the invention.

Figure 2 is a sectional view, taken on line 2—2 of Figure 3, illustrating its application.

Figure 3 is a sectional view taken on line 20 3—3 of Figure 2.

Figure 4 is a detail view of the bolt element used in the lock structure.

Figure 5 is a sectional view taken on line 5—5 of Figure 4; and

25 Fig. 6 is a fragmentary sectional view showing a slightly different form of bolt construction from that illustrated in Fig. 3.

Referring more in detail to the drawings, Figures 1 to 5 inclusive show a lock composed of a casing 25 having an outer or cover plate 26, enclosing marginal walls 27 and a partial bottom plate 28, containing openings 29, similar opening 30 being formed in the plate 26.

35 A keeper, having securing flanges 31 and 32 secured to the jamb of the door, is provided with upstanding, hook-like projections 33, freely insertible through the openings 29 and 30 in the lock casing, as best seen in Figure 40 2, being firmly anchored, and the extending plate 28 of the casing is disposed over the flange 31 when the door is closed.

A tumbler lock, generally designated by the numeral 34, is operated by a key 35 and 45 held in the door by the usual bolts 36 passing through a plate 37.

A square stem 38 extends from the lock 34, through the plate 37 into and through the lock casing 25 and has secured at its 50 outer end an operating knob 39.

A bushing 40 guides the stem through a removable cover plate 41, held by screws to the casing, and another bushing 42 in the cover plate 26, guides the stem 38 at its upper end adjacent the knob 39.

55

A stud 43, integral with the casing cover plate 26, extends into the casing, its end being in proximity to the plate 41, and encircling the stud is a sleeve 44. On said sleeve is mounted the bolt hub 45 which is provided with protruding bolts 46. Said bolts 46 are bevelled in the proper direction (Fig. 5) to allow the bolts to ride over the hooks 33 of the keeper when the door is swung shut, against the action of the tension spring 47. After the bolts pass the hooks 33, said spring 60 serves to retract the bolts, which consequently are swung under the hooks 33 into locking position. One end of the spring 47 is secured within the lock casing and the other to an arm 48 reaching rearwardly from the hub 45.

65

A plurality of teeth 49 on the upper part of the hub 45 are engageable with mating teeth 50 on a disc 51 secured to the sleeve 42 and thus it will be seen that upon rotating the knob 39 or the key 35, the bolts 46 may be moved into or out of engaging position, this movement being limited by an arm on the disc making contact with stop pins 53 and 54 set in the casing plate 26.

75

70 A screw 55 is adjustable in the plate 26 and adapted to engage in an opening 56 in the hub 45 when it is desired to positively maintain the bolts in a locked position.

80

75 The construction shown in Fig. 6 embraces a hub 45' having extended bolt portions 46' engageable with the keeper comprising elements 33'. The latter are undercut to receive extensions 46'' projecting from the side edges of the bolt portions. The operating mechanism may otherwise be the same as that afore-described.

85

80 Although the foregoing is generally descriptive of a preferred embodiment of my invention, it is probable that changes and modifications can be made therein and still be within the scope and spirit of the appended claims.

90

Having thus described my invention, what 100

I claim as new and desire to secure by Letters Patent, is:—

1. A lock comprising a casing, a stem rotatable therein, a stud integral with said casing, a hub rotatable thereon, operative connections between said stem and hub, bolts extending radially in spaced relation from said hub, and a keeper having hooked extensions engageable by said bolts. 70
10. A lock comprising a casing, a bolt having angularly disposed arms pivotally mounted therein, said arms extending integrally from a common center, means to actuate said bolt from either side of said casing, a keeper having overhanging portions engageable with said arms simultaneously, and means to normally maintain said arms and keeper elements in engagement. 75
20. A lock comprising a casing, a stem rotatable therein, a stud integral with said casing, a hub rotatable thereon, operative connections between said stem and hub, integral bolts extending angularly from said hub, a keeper having extending elements projecting through said casing to engage said bolts, and a spring urging said bolts into engagement with said keeper elements. 80
30. A door lock comprising a casing, a stem integral therewith, a sleeve on said stem, a hub rotatable on said sleeve, a pair of angularly disposed bolts integral with said hub, a keeper having raised hooks to pass through said casing, said hooks being engageable by said bolts, a tension spring attached to said hub to normally cause engagement of the bolts and hooks, spur teeth on said hub, a segmental pinion engaging said teeth, a stop for said pinion and means to impart a partial rotation to said pinion. 85
40. A door lock comprising a casing, to be secured to a door and having a part extending over an adjacent jamb thereof, said extending part having convergent openings, a keeper fixed to the door jamb, integral hook members on said keeper to pass through the mentioned openings, a pair of swinging bolts pivoted in said casing, means in said casing to normally cause said bolts to engage the keeper hook members and combined key and knob members operable to swing said bolts out of engagement with said hooks. 90
50. A door lock comprising a hollow casing to be fixed on a door and having a part extending past the jamb thereof, said extending part having one or more openings, a post extending integral inward from said casing, a hub rotatable on said post, one or more projections on said hub movable into the sphere of the openings, a keeper fixed on the jamb of the door, said keeper having hook-like elements to reach through the openings in said casing to engage said projections when swung thereunder, resilient means to normally rotate said projections into engagement with the hook-like elements, and manually operated means to swing said projections from their engaging position. 95
60. A door lock comprising a casing having an overhanging part containing openings, a keeper having elements insertible through said openings and presenting inreaching hooks, a bolt pivoted in said casing to engage the keeper elements, means for normally causing engagement, therebetween, means for manually moving said bolt out of engagement, and means to secure said bolt when in engagement. 100
70. A door lock comprising a casing having an overhanging part containing openings, a keeper having elements insertible through said openings and presenting inreaching hooks, a bolt pivoted in said casing to engage the keeper elements, geared means for rotating said bolt into and out of operative position, means to secure the bolt when in locked position, a stop for said geared means, and manually actuated means to operate said geared means. 105
80. A door lock comprising a casing having its front and side faces extended beyond the end of said bolt whereby a housing is formed integral with and at one end of said casing, said housing having a plurality of divergently inclined slots formed through its outer face, a keeper plate co-operating with said door lock keeper hooks on said plate to extend into said slots to prevent the keepers from being forced laterally, a rotatable bolt having elements to engage each keeper hook simultaneously, and key operated means to actuate the bolt. 110
90. In a lock for a door swinging about a vertical axis the combination of a casing containing the locking mechanism, adapted to be secured to the side of the door, a keeper adapted to be secured to a door jamb having hooks extending therefrom, a portion of said casing extending beyond the edge of said door and having a plurality of openings in its side adjacent to the door adapted to receive said hooks, and a spring tension bolt extending beyond the edge of the door and enclosed by said extending casing portion, said bolt having parts to engage said hooks, said hooks being radial with respect to the axis of said bolt when the door is swung in its closed position. 115
100. A door lock comprising a casing to be secured to a door having a part extending over an adjacent jamb thereof, said extending part having a plurality of spaced convergent rectangular openings, a keeper fastened to the door jamb, integral hook members on said keeper to pass through the mentioned openings, and a tensioned latch bolt pivotally mounted in the casing to engage the hooks of the keeper when the bolt is in operative position. 120
110. A door lock comprising a casing to be secured to a door having a part extending over an adjacent jamb thereof, said extending part having a plurality of spaced convergent rectangular openings, a keeper fastened to the door jamb, integral hook members on said keeper to pass through the mentioned openings, and a tensioned latch bolt pivotally mounted in the casing to engage the hooks of the keeper when the bolt is in operative position. 125
120. In a door lock comprising a casing to be secured to a door having a part extending over an adjacent jamb thereof, said extending part having a plurality of spaced convergent rectangular openings, a keeper fastened to the door jamb, integral hook members on said keeper to pass through the mentioned openings, and a tensioned latch bolt pivotally mounted in the casing to engage the hooks of the keeper when the bolt is in operative position. 130

be secured to a door and having a part thereof extending over the adjacent door jamb thereof, said extending part having a plurality of angularly inclined openings, a keeper fixed to the door jamb, integral hook members on said keeper to pass through the mentioned openings, and a spring actuated bolt movable in the casing and having an interlocking engagement with the keeper hooks when said bolt is in its engaging position.

10 13. In a door lock, the combination of a casing to be fastened to a door with the end of said casing extending over the space between the door and the door jamb and presenting a solid wall at its end, said extension having a plurality of spaced openings, a keeper plate fastened to the door jamb, hook members projecting from said keeper plate, a spring actuated mechanism mounted in 15 said casing, said mechanism comprising a bevelled member for each of the hook members, said bevelled members being integrally connected with each other and being all movable in the same direction for interlocking with said keeper plate, and each of said bevelled members arranged on closing of the door, simultaneously to strike against and ride over the corresponding hook of the keeper when said hook passes through the 20 openings of said casing, and key operated means to move the mechanism to its inoperative position.

14. A door lock comprising a casing to be secured to a door having a part extending over an adjacent jamb thereof and presenting a solid wall at its end, said extension having a plurality of spaced slots, a keeper plate fastened to the door jamb, a plurality of hooks projecting from said plate and adapted 25 to enter said slots, a spring actuated locking mechanism, said mechanism including a plurality of locking bevelled members integrally connected with each other and being movable in the same direction, when actuated by the hooks of said keeper upon the closing of the door, whereby said bevelled members will automatically interlock with said keeper and manually operated means to move said locking mechanism to its inoperative state.

30 15. A door lock comprising a casing to be secured to a door and having a part extending over an adjacent jamb thereof, said extending part having a pair of spaced openings and presenting a solid wall at the end thereof, a keeper plate fastened to said jamb, a pair of hooks extending from said keeper plate, said hooks adapted to pass through said openings, a spring operated bolt mounted in said casing and comprising a pair of locking bevelled members integrally connected 35 with each other and both movable in the same direction for interlocking engagement with said keeper, said bevelled members being arranged, upon the closing of the door, to strike and ride over both hooks of the keeper and

automatically interlock with the same and key operated means to move said locking members out of locking engagement with the hooks of said keeper.

16. A lock having a plurality of rockingly mounted locking members integrally connected with each other and movable in an arcuate path, a keeper plate having a plurality of similar spaced projections outstanding therefrom, a pivot for said locking members, mechanism to rock said locking members as a unit on said pivot, a casing for said mechanism having a portion thereof surrounding said locking members when said lock is in inoperative state, said casing portion having a plurality of spaced slots to receive said projections of the keeper plate and said locking members being adapted to interlock with said projections thereby locking the casing to the keeper plate, the extent of the rocking motion of said locking members being substantially equal to the width of one of the slots in the casing, spring means mounted in the casing for normally maintaining said locking members in operative state, and manually operated means for rocking said members as a unit out of operative engagement with the keeper plate.

17. In a door lock, the combination of a casing adapted to be secured to a door, and containing a locking mechanism, a keeper plate adapted to be fastened to a door jamb and having spaced projections extending therefrom, a portion of said casing being adapted to extend beyond the edge of said door and having spaced openings adapted to receive said projections, a plurality of pivotally mounted spaced locking members integrally connected to each other and adapted to extend beyond the adjacent edge of the door and enclosed by said extending portion, said locking members when actuated by the mechanism being arranged to move as a unit in an arcuate path through a distance substantially equal to the width of each of the openings and into the openings to engage the spaced projections simultaneously, and key operated means to actuate said locking members to release the same from locking engagement with the projections.

18. A door lock comprising a casing to be secured to a door, said casing having an extension projecting over the adjacent door jamb, said extension having a plurality of spaced slots, a keeper plate adapted to be fastened to the door jamb, a plurality of spaced apertured projections outstanding from said plate and adapted to enter said slots, a plurality of locking members integrally connected with each other and movable as a unit in the same direction for interlocking with the projections of said keeper plate and being pivotally mounted on a common pivot in said casing for movement in an arcuate direction into and out of the aper-

tures of the projections, the distance of the movement of said locking members in the extension of the casing being approximately equal to the width of the slots formed in said extension, mechanism mounted in the casing for simultaneously swinging said locking members on said pivot to release said members out of the locking engagement with the keeper plate, and key operated means to actuate said mechanism.

- 10 19. A lock having a plurality of pivotally mounted spaced locking members integrally connected with each other and swingable about a common pivot, a keeper plate for said locking members having outstanding projections spaced apart a distance equal to that between the members and adapted to interlock with the members, a casing enclosing said locking members, said casing overlapping said keeper and having spaced openings spaced apart a distance equal to that between the members for the reception of said projections, mechanism for rocking said locking members on said common pivot for withdrawing said locking members out of the interlocking engagement with the projections, the rocking movement of said members being approximately through a distance equal to the width of the openings, and manually operated means for rocking said locking members to disengage said members from the interlocking engagement with the keeper plate.
- 15 20. A lock having a plurality of rockingly mounted locking members, movable in an arcuate path as a unit, a keeper plate having a plurality of similar spaced projections outstanding therefrom, a pivot for said locking members, mechanism to rock said locking members as a unit on said pivot, a casing for said mechanism having a portion thereof surrounding said locking members when said lock is unlocked, said casing portion having a plurality of spaced slots to receive the projections of the keeper plate, and said locking members being adapted to interlock with said projections to lock the casing to the keeper plate, the extent of the rocking movement of the locking members being substantially equal
- 20 25 30

- 35 40 45 50 55 60 65 70 75 80 85 90 95 100 105 110 115 120 125
- to the width of one of the slots in the casing, a cover plate detachably secured to said casing, a bearing projection extending from the inner wall of said casing, the cover plate and the bearing projection being arranged to guide the locking members in their arcuate path to maintain the locking members against lateral displacement within the casing when said members are swung on said pivot into and out of locking engagement with the projections of the keeper plate, and manually operated means to actuate said mechanism for rocking the locking members as a unit out of operative engagement with the keeper plate.
- 66 21. In a lock, a plurality of spaced locking

members, a casing open at the rear face thereof, an oscillatory member within the casing integrally connected with and carrying said locking members and movable in an arcuate path together with said locking members, a keeper plate having a plurality of similar spaced projections outstanding therefrom, a pivot for said oscillatory member projecting from the casing into the interior thereof toward the open rear face thereof, mechanism to rock said locking members and the oscillatory member as a unit on said pivot, an extension on said casing surrounding said locking members when the lock is in unlocked position, said extension having a plurality of spaced slots to receive the spaced projections of the keeper plate, and said locking members being adapted to interlock with said projections to lock the extension to the keeper plate, the extent of the rocking movement of said locking members being substantially equal to the width of one of the slots in the extension, a cover plate removably secured to the rear face of the casing to cover the opening therein, a bearing projection for the oscillatory member extending from the inner face of the front wall of the casing toward the cover plate and adapted to engage one face of said oscillatory member, means on said oscillatory member extending toward said cover and cooperating with said cover and said bearing projection to maintain said oscillatory member and said locking members against displacement laterally of said casing, and a knob operatively connected to said rocking mechanism and arranged in front of the front face of the casing.

In testimony whereof I have signed my name to this specification.

JOHN HOLTZMAN.
